METHOD FOR HYDROCRACKING HIGH MOLECULAR WEIGHT HYDROCARBONS
Frank J. Jenny, 460 W. 24th St., New York 11, N.Y.
Filed May 19, 1960, Ser. No. 30,725
2 Claims. (Cl. 208—58)

This application is a continuation-in-part of my prior copending application Serial No. 491,988, filed March 3, 1955, now abandoned, which is a continuation-in-part of application S.N. 369,800, filed July 23, 1953, now abandoned, and of S.N. 6,303, filed February 4, 1948, now abandoned.

My invention relates to a method of hydrocracking high molecular weight hydrocarbons and more particularly to a novel and improved method for the economic processing of very heavy hydrocarbons, such as bituminous coals and heavy, high sulphur tars, to form gasoline and other valuable, normally liquid hydrocarbons.

There is a large and ever-growing interest in methods of increasing the value of primary fuels, that is, in upgrading them. Competition among the coal, natural gas and petroleum industries is increasing and methods of converting primary fuels of low cost into more valuable forms are being avidly sought. Specific interest is being directed more to the relative cost of the B.t.u. and less to cost per unit of weight or volume of the primary fuel. Frequently, fuels may be interchangeably employed. A properly designed and equipped utility installation for generating electric power should be operable either with solid, liquid or gaseous fuels. In such case, the choice of the fuel which is to be employed is controlled by the current economic conditions in the three competing fuels. The object always sought is the maximum number of B.t.u.'s for the fuel dollar.

The market value of a fuel, furthermore, is not completely governed by the cost of its production. In a locality adjacent a coal producing area, the market price of coal is easily competitive with natural gas, which must be transported hundreds of miles by interstate pipelines. Coal, furthermore, in a coal producing region is competitive with petroleum fuel oils, which must be transported either by tank car, pipeline or truck. When, however, coal must be transported appreciable distances, the cost of coal transportation, when added to the cost of the product at the mine, makes the price of coal prohibitive.

It will be clear that a method which can upgrade coal to the form of a liquid or gaseous fuel will reduce the cost of transportation per B.t.u. of the fuel and create a new market outlet for coal.

It is to be noted, further, that currently this country has reached a transition point from being a net exporter of petroleum products to being a net importer of them. This change is apparently due to the comparatively high cost of producing domestic crude oil. An additional and major factor is the large and constantly growing demand and the almost profigate consumption of higher grade petroleum products. Besides this, the long range availability of high quality crude oils is becoming increasingly less. Accordingly, there has been, and is, a pressing need for an economically and commercially feasible process which will convert heavy crude oils, and particularly those having a high sulphur content, into economically more valuable and more generally utilizable hydrocarbons. The difficulty of processing the so-called "high sulphur tars" makes them in large supply. Neither these nor bituminous coal are readily moved by pipeline, as are the high quality crudes.

It was pointed out in my copending application Serial No. 369,900, filed July 23, 1953, that high molecular

2

weight hydrocarbons cannot readily be cracked by conventional methods since large quantities of carbon are formed causing heavy carbon deposits to occur. Furthermore, the higher molecular weight hydrocarbons tend to decompose first and at lower temperatures. The problem inseparably associated with any method of cracking heavy hydrocarbons is that of supplying heat to the material being processed. In my copending application, heat is supplied to the cracking zone in three ways: first by the sensible heat of the hot synthesis gas which is freshly generated and passed into the hydrocracking zone; second, by the admission of oxygen into the hydrocracking zone so that some of the carbon formed in the hydrocracking zone is immediately burned to provide heat. The third mode of supplying heat disclosed in my copending application is that of preheating the charging stock in an atmosphere of hydrogen to prevent the formation of carbon deposits.

One object of my invention is to provide an improved method for upgrading primary fuels and particularly those in the range of heavy sulphur tars, bitumens, bituminous coals, tar sands, oil shales and the like.

Another object of my invention is to provide a novel and improved method for converting heavy hydrocarbons having low hydrogen-to-carbon ratios into more desirable gaseous and liquid fuels by hydrocracking in a novel, expeditious, convenient and economic method.

A further object of my invention is to provide a novel method of supplying heat to the hydrocracking zone.

A further object of my invention is to provide a process for converting primary fuels to more valuable fuels in which higher yields of the desired liquid fractions are obtained than heretofore achieved.

Other and further objects of my invention will appear from the following description.

In general, my invention contemplates the establishment of a fluidized or free flowing bed of char or coke from which a stream of char is constantly withdrawn for external heating by combustion of a portion of the char with an oxygen-bearing gas, such as air or the like. The superheated char is returned to the bed and may be superheated in its passage by the addition of oxygen as part of the transport gas. The bed of char is maintained in heated condition by the flow of freshly formed, hot synthesis gas, that is, a freshly formed mixture of carbon monoxide and hydrogen. The hydrogen in the heating gas furnishes the hydrogen atmosphere for the hydrocracking step. The heavy hydrocarbons charged to the process are introduced into the fluidized bed of char. These hydrocarbons may be preheated by the use of oxygen for controlled oxidation of a portion of the charge. Advantageously, if the charge is normally solid or super-cooled liquid, such as bituminous coal, the comminuted charge is admixed with an appropriate selective solvent, preferably one formed in the process.

The synthesis gas generator in my process acts as a scavenger, taking only the lowest grade residue fuels. High-grade gasoline and distillates are economically formed by my process.

The accompanying drawing which forms part of the instant specification and which is to be read in conjunction therewith is a diagrammatic view showing one form of apparatus capable of carrying out the process of my invention.

More particularly, referring now to the drawing, the charge, which may be any heavy hydrocarbon, such as properly pulverized bituminous coal or the like, from any appropriate source, passes through pipe 10 in fluid flow. It is known to the art that comminuted materials will act as liquids, if confined in a pipe or the like and fed in small quantity of a gas. The charge is pumped by

pump 12 through a mixing zone 14 into which a selective solvent passes through pipe 16. The hydroaromatic hydrocarbons, such as tetralin, decalin and other hydrocarbon fractions formed in the process, are appropriate solvents. The solvent, which is thus antecedently formed in the process, may be withdrawn from the bottom of fractionating tower 18 through pipe 20, past valve 22 and pumped by pump 24 through pipe 26 into pipe 16. If desired, solvent from any suitable source (not shown) may be pumped by pump 28 through pipe 30 past valve 32 into pipe 16. The solvent and the coal are thoroughly mixed by any appropriate means known to the art in the mixing zone 14. The quantity of solvent which is mixed with the coal may vary. The quantity is regulated to obtain substantial solubility of desired lighter fractions of the charge in the solvent. Thus, the fraction of coal dissolved may vary from about 15% to 50% of the charge. With charging stocks having conventional petroleum characteristics, such as heavy high sulphur tars, the percentage solubility of the charge may be up to as high as 80% to 90%. Depending upon the particular solvent used and the temperature at which the solution is effected, the weight of the solvent will vary between wide limits. In a typical case, as much as twice the weight of solvent with respect to the weight of charge may be employed.

As contemplated, the use of a selective solvent results in a higher yield of upgraded liquid product. In the processing of heavy oil liquid fractions which are very viscous, the solvent increases the fluidity of the charge. Thus, when the heavy oil solution is charged into the hydrocracker, there is a greater degree of uniform wetting of the virtually infinite surface for reaction as provided by the fluidized bed. Thus the tendency for localized mixing with viscous chargestocks is decreased and the resultant localized excessive coking reactions are minimized.

With solid fuels, the effect of solution is to attain a preliminary liquid phase depolymerization of the very high molecular weight compounds comprising the solid fuel. By immediately subjecting these dissociated high molecular weight fractions to an atmosphere of excess hydrogen, further hydro-depolymerization occurs with resultant increased volatility and improved overall liquid yields. Correspondingly, partial hydrogenation of the very highly unsaturated fragments is simultaneously effected which prevents repolymerization of such fractions. Thus there is both a decreased lower overall net yield of coke or char, and correspondingly a higher liquid yield of upgraded distillate fractions.

With high molecular weight hydrocarbons, such as bituminous coal, as the coal is preheated, it passes through a plastic temperature range during which it becomes very viscous and is rendered non-susceptible to conventional preheat for all practical purposes. In a similar manner, heavy petroleum fractions will deposit coke on the walls of a preheater tube which will eventually clog the tube and prevent further flow. This situation is aggravated by the temperature gradient required across the metal of the heater tube, which temperature gradient is necessary to effect heat flow into the hydrocarbon fraction being preheated. The hydrocarbon "film temperature" immediately adjacent the wall of the metal heater tube will be appreciably greater than the average hydrocarbon temperature in that section of the tube, thus inherently accelerating the formation of coke. This coke clings to the metal wall and builds up a permanent layer of coke. The charge is usually rich in gum-forming compounds which become manifest in the plastic temperature range. These gummy substances, if not properly counteracted, will preclude and prevent the formation of the fluidized bed which I desire in my process owing to the fact that the gummy substances will simply coalesce the coal particles and destroy the finely divided form necessary for fluidity. In order to preheat the charge and to selec-

tively burn off or oxidize gummy substances, I introduce oxygen into the preheating zone 34. The oxygen is taken from any suitable source (not shown) and passed through pipe 36, through pipe 38, past valve 40, into the oxidizing or preheating zone 34. It is to be understood, of course, that the oxygen is under any appropriate super-atmospheric pressure enabling it to be charged to the process. The oxygen may be substantially pure, if desired. Or it may be as low as 40% in purity. It will be appreciated that the purer the oxygen, the lower will be the quantity of inert gas which must be passed through the system and eliminated. Sufficient of the charge is oxidized to preheat the charge to a temperature as high as 850° F., if desired. Preferably, I heat the incoming charge to a temperature in the vicinity of between 500° F. and 600° F. The temperature of preheat is governed, on one hand, by the quantity of gum-forming compounds in the coal. I desire to remove these by conversion in order to be able to maintain a fluid bed in the reaction zone. On the other hand, the temperature of preheat is governed by the amount of solubility desired. Generally higher solubility ratios, that is, the percent of the charge to be dissolved, require a higher preheat temperature. The preheated charge passes through pipe 42 into the hydrocracking zone 44.

A gas rich in hydrogen, removed from the absorber 46, is pumped by compressor 48 through pipeline 50, through pipeline 52, past valve 54, through pipe 56 to the transfer pipe 58, through which hot synthesis gas from the synthesis gas generator 60 passes into hydrocracker 44.

I may introduce a low-grade carbonaceous fuel from any appropriate source through pipe 62, past valve 64, through pipe 66 in to the synthesis gas generator. It is to be understood, of course, that a portion of the waste gas flowing out of pipe 68 may be introduced through pipe 62 to the synthesis gas generator. At the same time, I may introduce a portion of the fluidized char withdrawn from the hydrocracker into the synthesis gas generator through transfer pipe 70 controlled by valve 72. Oxygen from pipe 36 is introduced into the synthesis gas generating zone within the synthesis gas generator 60 through pipe 74 under the control of valve 76. The generation of synthesis gas proceeds at temperatures above 1500° F., advantageously between 1800° F. and 3000° F. It will be understood, of course, that any ash formed in the synthesis gas generation zone, as would be the case when coal is charged to the process, may be removed through the pipe 61 by opening valve 63. The control of the oxygen supply controls the temperature. Steam from any appropriate source flows through pipe 78, through pipe 80, past valve 82, through pipe 84, and thence through the pipe 66 into the synthesis gas generator. The steam thus introduced with the portion of the charge will react with carbon to produce a mixture of carbon monoxide and hydrogen. The hot gases generated in the synthesis gas generator furnish a portion of the heat of hydrocracking and, at the same time, supply the hydrogen atmosphere for the hydrocracking step. It will be observed that essentially we have a high-temperature oxidation occurring in the synthesis gas generation zone.

Another portion of the char passes through conduit 86 under the control of valve 88. If desired, excess char may be withdrawn from the system through pipe 90 under the control of valve 92. Any appropriate gas may be introduced into the conduit 86 through pipe 94 to maintain the char in flowable condition. In this manner, the char is withdrawn from the hydrocracker and passed into a char-heating zone 96 where a portion of the char is consumed by oxidation to heat the char. Air is introduced into the char heater from any appropriate source through pipe 98 under the control of valve 100. While we had a high-temperature oxidation of the char in the synthesis gas generator 60, we now have a low-temperature oxidation of the char in the char heater 96.

The char may be heated to temperatures as high as 900° F. to 1500° F., if desired. I prefer, however, to heat the char to between 1100° F. and 1300° F. In order to maintain the char in a fluidized condition and to provide the impelling gas to return the char to the fluidized char bed within the hydrocracker 44, I may bleed a portion of the air from pipe 98 to pipe 102 under the control of valve 104 and introduce this air into the transfer duct 105 which returns the heated char to the hydrocracking zone. In order to provide an atmosphere of hydrogen, I introduce steam from any appropriate source through pipe 108, past valve 110 into the transfer duct 106. This will permit the conversion of some of the carbon into a mixture of carbon monoxide and hydrogen by reaction of the steam with the carbon of the char. Besides this, the steam helps aerate the returning char. In order to provide the heat for the endothermic reaction of the conversion of carbon and steam into a mixture of carbon monoxide and hydrogen, I introduce oxygen through pipe 112 under the control of valve 114. This oxygen may further heat the char and maintain it in highly heated condition for introduction into the hydrocracking zone at temperatures between 900° F. and 1500° F., and preferably between 1100° F. and 1250° F.

In order to maintain the temperature of the hydrocracker between 800° F. and 1500° F., with a preferred temperature range in the vicinity of 850° F. to 1300° F., I controllably introduce steam and oxygen into the hydrocracking zone. Steam from pipe 78 flows through pipe 116 under the control of valve 118. If the temperature gets too high, an excess of steam will reduce the temperature owing to the endothermic nature of the reaction of carbon with steam. If the temperature gets too low, the introduction of oxygen from pipe 36, through pipe 120, under the control of valve 122, will increase the temperature within the hydrocracking zone owing to the exothermic nature of the oxidation of either the coke, the heavy coke-forming hydrocarbons or other components.

The overhead product leaving the hydrocracker 44 through pipe 124 is cooled in heat exchanger 126 by heat exchange with any appropriate medium passing through pipe 128 and being withdrawn through pipe 130. The cooled overhead products comprise a mixture of various hydrocarbons including gasoline, distillate and some heavy hydrocarbons, as well as hydrogen, carbon monoxide, entrained carbon and some normally gaseous hydrocarbons. A great many of the fractions contained in the overhead product are especially susceptible to hydrogenation. Accordingly, some or all of the reaction products may be withdrawn from pipe 132, through pipe 134, under the control of valve 136 and passed to a hydrogenation apparatus, indicated by the reference numeral 138. Any appropriate hydrogenation process known to the art may be employed. For example, the hydrogenation process shown in U.S. Patent 2,674,634 may be advantageously used to hydrogenate all or a portion of the hydrocracked reaction products. The hydrogenated product is removed from the hydrogenation zone through pipe 140 and passed through pipe 142 to the fractionating tower 18. Recycle hydrogen for the hydrogenation step is supplied from the gases withdrawn from the absorber 46 through pipe 68. Accordingly, a portion of this hydrogen-bearing gas, which is being recycled to the hydrocracking zone, is withdrawn through pipe 144 under the control of valve 146 and passed to the hydrogenation zone as the hydrogen used in the hydrogenation process.

Normally, all or a portion of the reaction products from hydrocracking zone pass through pipe 148, under the control of valve 150, into pipe 142 and thence into the fractionating tower 18.

Recirculation of the hydrogen-bearing gas to the hydrocracking zone permits an independent selection of the operating pressure while maintaining a low partial pres-

sure of the reacting hydrocarbons. This facilitates the depolymerization reactions. As disclosed in copending application Serial No. 369,800, now abandoned, an intermediate hydrocarbon stream may then be withdrawn from the fractionating system to be recycled to the hydrogenation step for hydrogenation. A suitable stream would be recycled bottoms taken from the fractionating tower 18. The presence of an excess of hydrogen in the hydrocracking zone facilitates a partial sulphur reduction of high-sulphur hydrocarbon fractions by the maintenance of a high hydrogen partial pressure. This aids and abets conversion of the mercaptans and other sulphur compounds into hydrogen sulfide. Besides all this, the recirculated hydrogen gas fractions act as a carrier gas to ensure substantially completely stripping of the solvent vapors.

Where the quantity of hydrogen effectively produced in the synthesis gas generator 60 and in the transfer tube 106 is not adequate for over-all process requirements, the lower grade hydrocarbons removed from the bottom of the flash tower 150 may pass through pipe 152 under the control of valve 154 and be pumped by pump 156 past valve 158, thence into pipe 84 to the synthesis gas generator 60. In this manner, additional hydrogen in the form of synthesis gas will be produced. If desired, any excess flash tower bottoms may be recycled to the incoming charge.

The valve 160 maintains the fractionating tower 18 under a predetermined pressure. The higher boiling hydrocarbons removed from the fractionating tower 18 through pipe 20, which are not recycled by pump 24, pass by valve 164 through pipe 162 into the flash tower 150 and are flashed into vapors and heavy, normally liquid fuel oil-like hydrocarbons. The fuel oil flash tower improves the efficiency of the separation to a degree not obtainable in the fractionating tower and aids in the complete removal of the lighter, more economical, valuable hydrocarbons. The top of the flash tower is maintained at a predetermined temperature by reflux condensate pumped by pump 166 through pipe 168, past valve 170, through pipe 172 to the top of the tower 150. The bottom of the flash tower is maintained at a predetermined temperature by steam introduced through pipe 174 under the control of valve 176. The gases and vapors withdrawn from the top of the flash tower by pipe 180 are cooled in condenser 182 which is supplied with a cooling medium through pipe 184 under the control of valve 186. The condensate is withdrawn from the condenser 182 through pipe 188 and passed into a separator 190 from which any residual gas may be vented through pipe 192. A portion of the normally liquid hydrocarbons boiling within the distillate range is recycled as reflux condensate, as just pointed out. The balance of the distillate is withdrawn through pipe 194 under the control of valve 196 and passed to storage (not shown).

The distillate will be found to be especially high in aromatic hydrocarbons owing to the fact that the hydrocracker was operated at a preferred temperature of about 1100° F. This distillate, therefore, contains hydrocarbons which are especially valuable as a solvent for the heavy hydrocarbons being charged to the process. Accordingly, I may recycle a portion of the distillate through pipe 198 by opening valve 200, thus permitting the distillate to pass into pipe 26 and thence into pipe 16 for admixture with the hydrocarbons being charged to the process.

The normally gaseous hydrocarbons and vapors and normally liquid hydrocarbons are withdrawn from the top of the fractionating tower 18 through pipe 202 and flow past valve 160 through pipe 204 through condenser 206 which is supplied with a cooling medium by pipe 208 under the control of valve 210. The condensate leaves the condenser 206 through pipe 212 and flows into a separator 214. A pump 216 pumps a portion of the

condensate through pipe 218, past valve 220 for introduction to the top of the fractionating tower as reflux condensate. The balance of the condensate flows past valve 222 through pipe 224 into a stabilizer tower 266. The bottom of the stabilizing tower is maintained at a predetermined temperature by reboiler 267 supplied with a heating medium through pipe 268 under the control of valve 270. The vapors which comprise light hydrocarbons and normally gaseous hydrocarbons are withdrawn from the top of the stabilizer through pipe 272 and pass through a condenser 274 which is supplied with a cooling medium through pipe 276 under the control of valve 278. The condensate leaves the condenser 274 through pipe 280 and passes to a separator 282. Any normally gaseous products are withdrawn from the separator through pipe 284 under the control of valve 286. A portion of the condensate is pumped by pump 288 through pipe 290 under the control of valve 292 to the top of the stabilizer tower 266. The balance of the light hydrocarbons are withdrawn from the separator through pipe 294 under the control of valve 296. The stabilized gasoline-like hydrocarbons are withdrawn from the bottom of the stabilizer 266 through pipe 300 and pumped by pump 302 through a cooler 304 which is supplied with a cooling medium through pipe 306 under the control of valve 308. The cooled condensate comprising the desired gasoline is withdrawn from the cooler 304 through pipe 310 and passed to storage (not shown). A portion of the stabilized gasoline passes through pipe 312 and is pumped by pump 314 through pipe 316 to the top of the absorber 318 as the lean liquid menstrum. The gases and vapors withdrawn from the separator 214 through pipe 320 are introduced to the bottom of the absorber 46 for upward countercurrent contact with the lean menstrum. The enriched stabilized gasoline is withdrawn from the bottom of the absorber through pipe 322 and pumped by pump 324 into the stabilizer 266 through pipe 224 along with the condensate from separator 214. The normally gaseous hydrocarbons, the hydrogen, the unreacted carbon monoxide and any inert gases are withdrawn from the top of the absorber through pipe 328 past valve 330 and either vented to the atmosphere or recycled through pipe 50. This recycle hydrogen acts as a carrier gas to ensure substantially completely stripping of the solvent vapors in the reaction zone. As previously recited, the gas vented from pipe 68 may be passed to a synthesis gas generator for conversion of the gaseous hydrocarbons. It will be understood to those skilled in the art that synthesis gas can be converted to hydrogen of any desired purity by procedures well known in the art.

It will be observed that I have accomplished the objects of my invention. I provide a novel and improved process for the conversion of high molecular weight hydrocarbons having a low hydrogen-to-carbon ratio, such as bituminous coals, heavy high sulphur tars and the like, to form gasoline and other valuable, normally liquid hydrocarbons. I establish a bed of fluidized or free flowing char in a hydrocracking zone into which the hydrocarbons to be cracked are introduced. I circulate the char from the hydrocracking zone to a char heater and back to the hydrocracking zone. In the low-temperature heating of char, the carbon is converted into a mixture of carbon dioxide and steam which is vented from the stack of the char heater 96. A portion of the char is fed to the synthesis gas generator to produce the hydrogen atmosphere for the hydrocracker. In the high-temperature oxidation of char, the formation of synthesis gas, normally a mixture of hydrogen and carbon monoxide, is formed. The process is such that there is substantially a selective combustion of the lowest grade carbonaceous components with oxygen in the hydrocracker. Where coke or char is in excess and tends to build up, the formation of synthesis gas in the high-temperature oxidation of the char and the consumption of some of the char for purposes of supplying

heat to the reaction zone may be accelerated. This selective combustion occurs owing to the fact that heavy hydrocarbons with the highest carbon-forming tendencies have the lowest initial combustion temperatures and therefore will be the first to react with the oxygen which is directly added to the charge through pipe 38. The oxygen introduced through pipe 120 into the hydrocracker will have a like selective oxidation effect on the lowest grade hydrocarbons present in the hydrocracking zone. It will be seen that I employ oxygen as an extremely useful fuel, introducing it into the process in five different places. There has always been a psychological prejudice in the art to the investigation of the use of oxygen as a process tool. It must be carefully controlled since the reaction with the highly combustible hydrocarbons and oxygen is rapid and active. The temperature at which oxygen is introduced must be such that it will immediately react and thus serve its intended purpose. The use of oxygen prevents the formation of gum-forming compounds which will prevent the formation of a fluid bed. It will be observed that the charging stocks comprising the heavy hydrocarbons to which my process is peculiarly adapted have low hydrogen-to-carbon ratios and cannot, accordingly, be cracked by methods known to the prior art to produce desired gasoline-like hydrocarbons. I correct the deficiency in hydrogen in my process in two ways. First, I reduce the carbon by the hydrocracking process in the presence of an excess of hydrogen. Besides this, I add hydrogen to the overhead products removed from the hydrocracker in a separate hydrogenation zone. Owing to the low hydrogen-to-carbon ratio, an excess of carbon is formed in the process. This carbon is converted into the synthesis gas and into heat and recycled to the process. Thus, I correct the deficiency by increasing the hydrogen-to-carbon ratio in the desired product and eliminating the excess carbon as coke or char. When the process conditions are correctly adjusted, sufficient carbon may be eliminated so that the only hydrogenation which is needed in the hydrogenation zone will be a mild one which will aromatize the hydrocarbons formed in the process, aid in gum removal and in the removal of sulphur in the form of hydrogen sulfide. It is to be understood, of course, that if a high sulphur tar is being charged to the process, the gases removed from the absorber may be passed to a hydrogen sulfide removal step (not shown) before recycling. By my process the lowest grades of primary fuels are economically converted into more valuable, lower-boiling liquid hydrocarbons. It is to be remembered, however, that the effluent from the hydrocracking zone contains all of the necessary components for hydrogenation. The vaporized distillate present in the effluent has fractions of a low hydrogen content. The effluent contains hydrogen which is present in the unreacted synthesis gas. This mixture can readily be converted in hydrogenation apparatus to a primary fuel of a specification grade distillate. I prefer to hydrogenate a portion of the reactor effluent since the heavier of the normally liquid, unsaturated hydrocarbons formed in the process will repolymerize in liquid phase if not hydrogenated. It will also be observed that the hydrogenation ordinarily occurs at a lower temperature than the hydrocracking step so that it will not be necessary to reheat the effluent from the hydrocracker on its way to the hydrogenation zone.

It will also be observed that the distillate formed in the process is especially suitable as a solvent for the heavy hydrocarbons being charged to the process and may be conveniently recycled to effect substantially selective solution of desired components. It will, of course, be understood that the use of other solvents is also contemplated. Such other solvents include the classification of paraffins, and preferably isoparaffins which react chemically with the highly unsaturated fragments of the cracking reaction to form new and useful compounds by alkylation and other condensation type reactions. The recycling of a hydrogen-rich gas to the reactor facilitates an additional degree of

freedom in operating the process. This recycle H₂ may be of any desired purity consistent with the activity of the specific hydrogenation catalyst used in the hydrogenation process. Pressure is not critical and any appropriate pressure may be employed for the operation of my process. The heat of the reaction is maintained preferably by a selective oxidation of carbonaceous solids. My process is continuous. After I establish a circulating ring of char from the fluid char bed to the char heater and back to the hydrocracking zone, the amount of char which is bled from this circulating ring to the synthesis gas generator will depend on process conditions and the proportion of excess carbon in the charging stock. Heavy hydrocarbons formed in the process are recycled to the reactor where they may be effectively hydrocracked.

I have provided an improved method for upgrading primary fuels, and especially those in the range of heavy sulphur tars, bituminous coals, tar sands, oil shales and the like, for which no economically feasible cracking process is provided by the prior art. I have provided an improved method for converting heavy hydrocarbons having low hydrogen-to-carbon ratios into more desirable gaseous and liquid fuels. My hydrocracking method for heavy hydrocarbons includes a unique mode of supplying heat to the hydrocracking zone.

Advantageously, I upgrade the hydrocracked distillate fractions from the hydrocracking stage by a second stage reaction. These distillate fractions are conveniently hydrogenated to produce normally liquid fractions of improved product quality.

For this second stage reaction, I may also employ other methods for producing normally liquid fractions of improved product quality. Thus, the solvent used in my hydrocracking stage is vaporized and carried to the second stage. By employing suitable alkylating temperatures, pressures and catalysts, condensation products are formed with hydrocracked unsaturated fractions to form premium quality liquid fuels.

As desired, depending upon the particular high molecular weight hydrocarbon being hydrocracked, I may also use a catalytic reforming, or hydroforming stage, as my second stage reaction. In practicing hydroforming, where dehydrogenation reactions may predominate in the con-

version of saturated and cyclic hydrocarbons to aromatics, the excess hydrogen serves as a source of hydrogen for the hydrocracking reaction process. Suitable hydroforming and alkylation or condensation type process are known in the art.

It will be understood that certain features and sub-combinations are of utility and may be employed without reference to other features and subcombinations. This is contemplated by and is within the scope of my claims. It is further obvious that various changes may be made in details within the scope of my claims without departing from the spirit of my invention. It is therefore to be understood that my invention is not to be limited to the specific details shown and described.

15 I claim:

1. In a process for the conversion of hydrocarbons wherein a hydrocarbon is subjected to cracking in a cracking zone in the presence of a substantial flow of a free hydrogen containing gas, the improvement of upgrading hydrocracked fractions which comprises withdrawing hydrocarbon vapors and hydrogen from said cracking zone, subjecting said hydrocarbon vapors and hydrogen to reaction in a hydrogenation zone at effective hydrogenation temperatures and pressures and in the presence of a hydrogenation catalyst, separating the products of hydrogenation into vapor and liquid fractions, and recovering a hydrogenated liquid hydrocarbon.

2. A process as in claim 1 in which said cracking includes coking and in which said cracking and coking reactions occur in contact with a fluidized bed of coke particles.
